SKI-TYPE SNOW VEHICLE

Arthur W. Loerke, 120 Kearney St.,
Denver, Colo. 80220

Filed Aug. 27, 1968, Ser. No. 13,294

Term of patent 14 years

Int. Cl. D21—02
U.S. Cl. D34—15

FIGURE 1 is perspective view of a ski-type snow vehicle showing my new design;

FIGURE 2 is a side elevational view thereof, the opposite side being a mirror image;

FIGURE 3 is a top view of the frame shown in FIGURE 2;

FIGURE 4 is an end elevational view of the rear of the frame shown in FIGURE 2;

FIGURE 5 is an end elevational view of the front of the frame shown in FIGURE 2; and

FIGURE 6 is a bottom view of the frame shown in FIGURE 2.

The dominant features of my new design are shown in solid lines.

I claim:

The ornamental design for a ski-type snow vehicle, as shown and described.
